UNITED STATES PATENT OFFICE.

HENRY REUBEL, OF NEW YORK, N. Y., ASSIGNOR TO THE JOHN KRODER & HENRY REUBEL COMPANY, OF NEW YORK, N. Y., A CORPORATION OF NEW YORK.

DRAPEY SUPPORT.

Application filed April 2, 1924. Serial No. 703,591.

To all whom it may concern:

Be it known that I, HENRY REUBEL, a citizen of the United States, a resident of New York, in the county of New York and State of New York, have invented a certain new and useful Drapery Support, of which the following is a specification.

The invention relates to drapery supports of the type embodying a hollow guide having a longitudinal slot in one face, the walls of the guide on opposite sides of said slot being employed as tracks for a plurality of carriers which support the drapery and have suitable runners adapted to slide along the tracks during adjustment of the position of the drapery.

The primary object of the invention is to provide a drapery support of the above character in which the carriers will slide freely under all conditions of use without jamming or clogging during adjustment of the drapery.

Further objects and advantages of the invention will be in part obvious and in part specifically pointed out in the description hereinafter contained which, taken in connection with the accompanying drawings, discloses certain preferred embodiments of the invention, such embodiments, however, are to be considered as merely illustrative of its principles. In the drawings—

Figure 1 is a side elevation partly in section of a drapery support constructed in accordance with the invention and mounted in operative position.

Figure 2 is a transverse sectional view of the drapery support appearing in Figure 1, taken on line 2—2 of Figure 1 and looking in the direction of the arrows.

Figure 3 is a longitudinal section showing detached one of the intermediate members forming a part of the drapery support shown in Figures 1 and 2, and

Figures 4 and 5 are views similar to Figures 2 and 3 respectively, but showing the modified form of intermediate member.

The invention is illustrated as used in connection with a hollow guide 1 having therein a longitudinal slot 2 and the walls 3 of the guide on opposite sides of the slot are shaped to provide a pair of tracks extending longitudinally of the guide. The carriers are shown as provided with suitable runners 4 adapted to slide or roll along the

tracks above mentioned, such runners in the present instance consisting of wheels or rollers carried by an axle 5.

In accordance with the present invention there is provided between the runners 4 an intermediate member 6 which is in the form of a solid block supported by the axle 5 and running in the slot 2 above mentioned, the side faces 7 of the block 6 having sufficient clearance from the edges of the tracks 3 to permit the carrier to move freely along the guide 1 and yet if the axle 5 tends to turn to the position substantially oblique to the guide 1, the side faces 7 of block 6 will engage the edges of tracks 3 and prevent the runners 4 from moving to such an oblique position as will jam the carrier in the guide.

The blocks 6 are made large enough to project longitudinally beyond the runners 4 as appears most clearly in Figure 1 whereby if adjacent carriers engage each other the end surfaces of the block 6 will act as bumpers to prevent the runners of the carriers from engaging each other. It is found that when adjacent carriers engage, particularly if the wheels rub together, the carriers tend to shift laterally and if the wheels or other parts of the carrier are of such construction that they may lock together, the carriers become jammed. But if the block 6 of the above character be employed the end surfaces of the block form bumpers extending substantially across the full width of the slot 1 and such surfaces are smooth, whereby they will not interlock or interfere with a certain amount of side play between the carriers.

The block 6 is provided with a hole 8 (Figure 3) through which the axle 5 passes and, preferably, this hole is substantially in a central, vertical, transverse plane of the block whereby the latter naturally hangs in mid position beneath the axle but may be tilted readily in either longitudinal direction when the draperies are pulled. Preferably the top of the block 6 lies somewhat beneath the tops of the runners 4 as appears in Figure 2, whereby the runners may run against the upper surfaces of the guide 1, under some conditions, and whereby the tilting of the block 6 will not cause it to rub against the guide.

The type of block shown in Figures 1 to 3 may be readily made out of cylindrical rod stock with the holes 8 drilled through

off-center so that each block 6 is eccentrically mounted upon its axle 5. The weight of blocks of the above nature is sufficient to urge them strongly toward a central 5 pending position and the relatively heavy weight also assists in keeping the runners on the tracks.

A drapery supporting member, such as the eye 9 shown in Figures 1 and 3, will be 10 carried by the block 6. As shown in Figures 1 to 3, a hole 10 may be made in each block providing a seat 11 at the bottom of the block upon which rests an enlarged head 12 upon the eye 9, thus forming a swivel 15 support for the eye.

A somewhat modified form of the invention is shown in Figures 4 and 5 wherein the block 6^a is provided with an eye 9^a made integral therewith, this embodiment of the 20 invention being suitable where a swivel eye is not desired. The block 6^a of Figures 4 and 5 may be made of oval bar stock and drilled to provide the eye 9^a and a hole 8^a corresponding to the hole 8 previously described in connection with Figures 1 to 3.

While certain specific embodiments of the invention have been described it will be obvious that many changes may be made therein without departing from its principles as defined in the following claims:

1. A drapery support comprising a hollow guide having a longitudinal slot therein, the walls of said guide on opposite sides of the slot constituting tracks extending lengthwise 35 of the guide, and a carrier, said carrier comprising runners fitting in said tracks and connected by an axle, and an intermediate member disposed in said slot, said intermediate member comprising a block through 40 which the axle passes in a substantially central vertical transverse plane of the block whereby the latter may tilt longitudinally of the slot in either direction about the centre of the axle as an axis, said block extending

longitudinally of the slot beyond the rollers 45 in both directions, whereby its end surfaces form bumpers extending substantially across the above-mentioned slot to prevent adjacent carriers from jamming, the sides of said block fitting relatively close to the edges of the slot to prevent substantial obliquity of the runners, said block having a hole therethrough providing a seat at the bottom thereof, and a swiveled drapery support resting upon said seat. 55

2. A drapery support comprising a hollow guide having a longitudinal slot therein, the walls of said guide on opposite sides of the slot constituting tracks extending lengthwise of the guide, and a carrier, said carrier comprising rollers fitting in said tracks and connected by an axle, and an intermediate member disposed in said slot, said intermediate member comprising a cylindrical block eccentrically offset with regard to the rollers whereby its upper surface lies below the upper surface of the rollers, said axle passing through a substantially central vertical transverse plane of the block whereby the latter may tilt longitudinally of the slot in either direction about the centre of the axle as an axis, said intermediate member being of larger diameter than the rollers whereby it extends longitudinally of the slot beyond the rollers in both directions and its end surfaces form bumpers extending substantially across the above mentioned slot and protruding beyond the rollers sufficiently to prevent adjacent carriers from jamming, the sides of said block fitting relatively close to the edges of said slot to prevent substantial obliquity of the rollers, and a drapery supporting member carried by said block. 70 75 80 85

In testimony that I claim the foregoing, I have hereunto set my hand this 21st day of March, 1924.

HENRY REUBEL.
